UNITED STATES PATENT OFFICE

159,660

BED

Albert Nero, Oakland, Calif.

Application May 10, 1949, Serial No. 2,541

Term of patent 7 years

(Cl. D5—4)

To all whom it may concern:

Be it known that I, Albert Nero, a citizen of the United States, residing at Oakland, in the county of Alameda and State of California, have invented a new, original, and ornamental Design for a Bed, of which the following is a specification, reference being had to the accompanying drawing, forming a part thereof.

Figure 1 is a side elevational view of a bed, showing my new design;

Figure 2 is a top plan view;

Figure 3 is a partial sectional view taken along the line 3—3 of Figure 2;

Figure 4 is an elevational view of the foot end of the bed.

The dominant features of the design reside in those portions shown in full lines.

I claim:

The ornamental design for a bed, as shown and described.

ALBERT NERO.
